UNITED STATES PATENT OFFICE.

JAMES B. ERWIN AND ORLANDO R. ERWIN, OF MILWAUKEE, WISCONSIN.

APPARATUS FOR AND PROCESS OF GENERATING FOAM.

1,214,660.

Specification of Letters Patent.

Patented Feb. 6, 1917.

Application filed February 14, 1916. Serial No. 73,118.

To all whom it may concern:

Be it known that we, JAMES B. ERWIN and ORLANDO R. ERWIN, citizens of the United States, residing in the city of Milwaukee, county of Milwaukee and State of Wisconsin, have invented new and useful Improvements in Apparatus for and Processes of Generating Foam, of which the following is a specification.

10 Our invention relates to improvements in apparatus for and process of generating foam for extinguishing fires, and it pertains to that class in which two foam producing liquids are brought together and 15 caused to chemically unite to form a fire extinguishing foam preparatory to being discharged upon a fire.

Our invention is explained by reference to the accompanying drawings, in which—
20 Figure 1 represents a vertical section thereof in connection with an air pump, a side view of which is shown, by which air is compressed and used for forcing and discharging said fire extinguishing liquids 25 upon a fire. Fig. 2 is a similar view to that shown in Fig. 1, part broken away showing a receptacle for compressed gas connected to said apparatus.

Like parts are identified by the same reference numerals throughout both views.
30 1 represents a liquid-tight receptacle of ordinary construction, and the same is provided with a partition 2 which is preferably located substantially at the center of said receptacle whereby the liquids 3 and 4 are separated from each other.

5 represents an air pump of ordinary construction by which air is compressed and forced therefrom through the duct 6 into 40 the upper end 7 of said receptacle 1, whereby said liquids 3 and 4 are simultaneously forced up through the ducts 8, 8 into the central duct 10 in which duct 10 they are commingled and converted into a foam, 45 which foam is discharged through an outlet nozzle 11 upon the fire. The central duct 10 is preferably made of larger area than the ducts 8, 8, whereby space is formed for generating the foam, as stated.

50 12 is a stuffing nut which is employed for forcing the packing 13 in close contact with said discharge duct 10 and said receptacle 1, whereby the compressed air is prevented from escaping around said duct 10. 14 is 55 a removable cap which is connected with the receptacle 1 by a screw threaded joint

15, whereby when said cap is removed said liquids 3 and 4 are readily inserted in the compartments 16 and 17 preparatory to operating the device. It will, of course, be understood that when said liquids 3 and 4 have been put in place said cap 14 is again connected with the receptacle 1, as shown. It will also be understood that the lower end of the pump 5 is readily detached from the lower end of said receptacle 1 by removing the screw 18.

19 is a handle by which the extinguisher may be transported from one place to another.

While the pump 5 shown is adapted to discharge air with each upstroke of the handle 20 it will be understood that the construction of said pump may be varied as is well known to the art, whereby air may be forced into the receptacle 1 by a down stroke. It will also be understood that said pump is provided with ordinary check valves, not shown, whereby air which has been forced to the receptacle 1 is prevented from returning to the pump with either stroke of the piston.

It will be understood that a receptacle 21 containing compressed gas may be substituted for the pump 5, when by opening the valve 22 the gas will escape from said receptacle into said receptacle 1 through the duct 23, whereby said fire extinguishing liquids 3 and 4 will be forced therefrom as stated.

It will be seen that the partition 2 extends with its upper edge above the edge of the receptacle 1 and within the cap 14 whereby the fluid 3 and 4 may assume levels above the upper edge of the receptacle 1 and within the cap 14 while the connections between the outlet ducts 10 and branch ducts 8 being within the cap 14 prevents any loss of fluid through leakage.

Having thus described our invention what we claim as new and desire to secure by Letters Patent, is:—

1. In a device of the described class, the combination of a liquid receptacle, a partition subdividing said receptacle into two compartments, a cap for said receptacle, two branch ducts communicating with each other within the said cap substantially centrally between the said cap and the upper edge of the said partition and respectively extending into the said compartments, a central third duct communicating with the

said branch ducts within the cap and extending therethrough, with a discharge nozzle upon said central duct, and means for applying pressure to the surface of the liquids in said compartments, whereby the same are commingled, converted into foam and discharged together through said nozzle upon a fire.

2. A fire extinguisher comprising a receptacle, a chambered cap upon the receptacle, a transverse partition within the receptacle terminating within the said cap and providing receiving chambers within said receptacle and cap, branch outlet pipes arranged within the said chambers spanning

the upper end of the said partition within the chamber of the cap, an enlarged outlet pipe connected to the said branch pipes and centrally extending through the said cap and fluid pressure producing means communicating with the said chambers through the said cap. 20

In testimony whereof we affix our signatures in the presence of two witnesses.

JAMES B. ERWIN.
ORLANDO R. ERWIN.
